UNITED STATES PATENT OFFICE.

FRANK KUHN AND JAY A. HAND, OF DETROIT, MICHIGAN, ASSIGNEES TO AMERICAN ELECTRICAL HEATER COMPANY, OF DETROIT, MICHIGAN, A CORPORATION OF MICHIGAN.

DESIGN FOR AN ELECTRIC-HEATER CASING.

53,417.

Specification for Design.

Patented June 10, 1919.

Application filed February 21, 1918. Serial No. 218,586. Term of patent 14 years.

To all whom it may concern:

Be it known that we, FRANK KUHN and JAY A. HAND, both citizens of the United States of America, both residing at Detroit, in the county of Wayne and State of Michigan, have invented a certain new, original, and ornamental Design for an Electric-Heater Casing, of which the following is a specification, reference being had therein to

the accompanying drawings, forming part thereof, in which the figure is a perspective view of a heating-unit casing showing my new design.

We claim:

The ornamental design for an electric heater casing, substantially as shown.

FRANK KUHN.
JAY A. HAND.
